CLAIM

The ornamental design for a controller, as shown and described.

DESCRIPTION

FIG. 1 is a front perspective view of a controller showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is another front perspective view thereof, where the controller is shown in a state of use where it is attached to an example charging device.

The broken lines in the figures depict portions of the controller in FIGS. 1-9, and an example charging device in FIG. 9 that is shown as environment. The broken lines form no part of the claimed design.
